SAFETY RAZOR

Joaquin Martorell, New York, N. Y.

Application June 5, 1935, Serial No. 25,175

3 Claims. (Cl. 30—56)

This invention relates to an improved safety razor and blade and the object of the invention is to provide an improved safety razor blade and holder, the latter consisting of a guard so constructed that it can be readily adjusted to accommodate blades of different widths; and which guard is also provided for retaining the blade thereon without need of a cap as now generally required by existing types or constructions of blade holders.

The invention together with its objects and advantages will be best understood from a study of the following description taken in connection with the accompanying drawing wherein:

15 Figure 1 is a top plan view.

Figure 2 is a side elevational view thereof.

Figure 3 is a detail sectional view.

Figure 4 is a plan view of the blade.

Referring to the drawing by reference numerals it will be seen that the razor comprises a guard consisting of a pair of substantially identical rectangular guard plates 7 and 8 respectively. The plates 7 and 8 as shown in Figure 3 are provided on their top faces with alternating grooves and ridges indicated generally at 9 to provide suitable guard fingers for the plates. At the outer edges and adjacent each of two corners thereof each plate has formed integrally therewith a pair of blade retaining hooks 10 and 11 as best shown in Figures 1 and 2.

At their meeting edges the plates 7 and 8 are formed with depending aprons or flanges 12 and 13 and for maintaining the plates in alignment and to facilitate the adjustment of the plates relative to one another, one of the skirts or aprons, for example the apron 13 has extending therefrom, a pair of guide pins 14 which operate in suitable openings provided in the other of the skirts or aprons, namely the skirt or apron 12.

40 Secured to one of the skirts or aprons, in the present instance, the skirt or apron 13 is a handle 15 which has a flat shank portion riveted as at 16 to the skirt 13 as shown in Figures 2 and 3.

For adjusting the plates relative to one another and for securing the plates at the desired adjustment, there is provided an adjusting screw 17 that extends through aligned openings in the plate 13 and shank of handle 15 and has threaded engagement with an opening in the skirt 12 as also clearly shown in Figure 3.

As indicated, a suitable single or double edge blade such as shown in Figure 4 and indicated by the reference numeral 18 may be placed in the holder resting on the guard plates 7 and 8 with opposite corner edge portions of the blade engaged under the hooks 10 and 11. Obviously by rotating the screw 17, the plates 7 and 8 will be easily adjusted toward or away from one another as required by the width of the blade 18.

60 In connection with the above, it will be ap-

parent that by moving the plates 7 and 8 into close relation the blade 18 may be held in a transversely curved position for use where a curved blade is desired.

It will be apparent that from the above, the razor can be cheaply and economically constructed, will accommodate blades of varying size, structure and make and will meet all the requirements of a safety razor of this character. Also, it will be noted that the improved blade 18 is imperforate, and being free of slots, apertures, and the like will have greater tensile strength and be more durable than the now existing safety razor blades.

Having thus described the invention, what is claimed is:—

1. In a safety razor, a pair of complementary guard plates each provided adjacent one edge and at opposite corners with blade engaging means, said blades at their meeting edges being provided with depending skirts, guide fingers extending from one of said skirts and through openings in the other of said skirt for holding said plates in substantially the same plane to facilitate adjustment of the plates laterally relative to one another, and an adjusting screw extending through openings in said skirts having threaded engagement with one of the skirts for adjusting the guard plates and for securing said plates at the desired adjustment.

2. In a safety razor, a pair of complementary guard plates each provided adjacent one edge and at opposite corners with blade engaging means, said plates at their meeting edges being provided with depending skirts, guide fingers extending from one of said skirts and through openings in the other of said skirts for holding said plates in substantially the same plane to facilitate adjustment of the plates laterally relative to one another, an adjusting screw extending through openings in said skirts having threaded engagement with one of the skirts for adjusting the guard plates and for securing said plates at the desired adjustment, and a handle member secured to the skirt of one of said plates.

3. In combination, a safety razor including a guard comprising a pair of complementary individual and mutually separated plates, each provided with means for engaging an edge of a blade, inter-engageable means on said plates for maintaining said plates in substantially the same plane when said plates are relatively moved toward or away from one another, means for adjusting the plates relative to one another and for securing the plates at the desired adjustment, and a blade comprising an imperforate body adapted to rest on said plates in either a flat or transversely curved condition.
